UNITED STATES PATENT OFFICE.

CHARLES H. SMOOT, OF NEW YORK, N. Y.

COUNTER-CURRENT INTERCHANGER.

1,238,053.

Specification of Letters Patent. Patented Aug. 21, 1917.

Application filed January 6, 1913, Serial No. 740,343. Renewed January 4, 1917. Serial No. 140,656.

To all whom it may concern:

Be it known that I, CHARLES H. SMOOT, a citizen of the United States, and resident of the city of New York, in the county and 5 State of New York, have invented certain new and useful Improvements in Counter-Current Interchangers, of which the following is a specification.

My invention relates to an interchanger in 10 which an exchange of heat is effected between counter-currents of air or other gas or fluid; more particularly in an interchanger designed to be used for progressively cooling a supply of compressed air as a preliminary step to its liquefaction, either in 15 whole or in part, by means of cold expanded air or the cold vapor products obtained from the rectification and separation into its elements of previously liquefied air, although 20 it may be found equally available for many other purposes.

The object of the invention is to provide an interchanger which can be easily and cheaply constructed, and which is more efficient than the interchangers heretofore used because of the greater extent of its conducting surfaces by which the interchange of heat, which is transmitted both by radiation and by conduction, is largely effected.

With this object in view, my improved interchanger consists, broadly stated, of an insulated volute bank of adjoining heat-interchanging passages formed by and between two plates of suitable heat-conducting material, such as copper, which are suitably spaced apart and coiled in volute form with a packing of wool-felt or other suitable non-conducting material between the several turns of the coil to insulate each from the other, and a series of parallel partition walls also of heat-conducting material, which divide the volute space between the two plates into a series of longitudinal passages extending from the inner to the outer ends of the plates, alternating passages being connected together in one series and the intermediate passages in another series, by means of manifolds or in any other suitable manner, both at their inner and outer ends.

For convenience in manufacture, I prefer to use small copper tubes, preferably round in section, to hold apart and to form the longitudinal passages between the two coiled plates. The walls of the tubes, suitably spaced apart and preferably soldered 55 to the plates so as to increase the area of

contact between tubes and plates, constitute partition walls which divide the volute space between the plates into a series of tubular conduits or passages, within the tubes, and 60 a series of intermediate passages, between the tubes; and, when a current of air or other gas or fluid which is to be cooled or heated, as the case may be, is forced in one direction through one series of passages, the 65 tubes for example, and the cooling or heating medium, through the intermediate passages, in an opposite direction, the exchange of heat takes place both by radiation through the thin walls of the tubes which alone 70 throughout their length separate the adjoining passages and by conduction in and through the walls of the tubes and the plates which have been made practically continuous.

The interchanger is quickly and easily made by placing a series of straight tubes between two flat plates and soldering them in position, each tube to both plates or for convenience alternate tubes to each of the 80 two plates and then laying a sheet of wool-felt over the outside of one of the plates and rolling plates, tubes and insulation up into a coil. The manifolds, which need not be of conducting material, may be secured to the 85 ends of the tubes and plates either before or after they have been coiled up; but, for convenience, the manifolds are preferably secured to the inner ends of the tubes and plates before the coil is formed, and the 90 manifold connecting the intermediate passages, which will naturally be larger than and surround the manifold connecting the tubular conduits and which if desired may be made large enough to contain an expansion motor or other liquefying device or both liquefying and rectifying apparatus, may be made to serve as a cylinder or drum upon which the coil is wound. The entire 95 interchanger coil is preferably insulated 100 from the atmosphere and protected by a suitable outer packing and casing.

The construction will be understood by reference to the accompanying drawings, in which one embodiment of the invention is 105 illustrated and in which—

Figure 1 is a sectional view of an interchanger and surrounding cylindrical casing on the line 1 1 of Fig. 2; Fig. 2, a section, partially broken away, on the line 2 2 of 110 Fig. 1; Fig. 3, a broken detail, partly in section, showing the manifolds secured to

the inner ends of the plates and tubes and the way in which the winding of the coil is begun; and Fig. 4, a broken detail, showing tubes, plates, and a sheet of insulating material as arranged preparatory to rolling them up into a coil.

Similar reference numerals indicate like parts throughout the several figures.

As here illustrated, the plates 1 and 2 and the tubes 3, placed between and secured in position in contact with the plates, form a coiled bank of alternating tubular conduits 4 and intermediate passages 5, and a non-conducting packing 6 insulates the turns of the coil from each other and the entire coil from the outside atmosphere. The inner and outer ends of the tubes are open to and connected together by the manifolds 7 and 8, respectively, and in similar manner the inner and outer ends of the intermediate passages are respectively opened to and connected together by the manifolds 9 and 10. The cylindrical casing 11, which surrounds the coil, is split along one side to form an opening through which the outer ends of the plates and inclosed tubes project, and its ends are closed by heads 12, only one of which is shown. Any suitable connections may be provided by which to supply to the manifold 8 and withdraw from the manifold 7 the air, gas, or other fluid which is to be cooled or heated, as the case may be, and by which the cooling or heating medium is supplied to the manifold 9 and withdrawn from the manifold 10.

It will, of course, be understood that the device may be variously modified in its details, within the scope of the appended claims, without departing from the spirit or sacrificing the advantages of my invention.

What I claim as new, and desire to secure by Letters Patent, is—

1. In apparatus of the character described, an insulated volute bank of adjoining heat-interchanging passages formed by and between two plates of heat-conducting material which are spaced apart and coiled in volute form with a packing of non-conducting material between the several turns of the coil, and a series of parallel partition walls of heat-conducting material which divide the volute space between the plates into longitudinal passages extending from the inner to the outer ends of the plates.

2. In apparatus of the character de-

scribed, two plates of heat-conducting material spaced apart and coiled in volute form and having the several turns of the coil insulated from each other by a packing 60 of non-conducting material, partition walls of heat-conducting material dividing the insulated volute space between the plates longitudinally into a bank of adjoining passages, and means connecting alternate 65 passages together in one series and intermediate passages in another series both at their inner and outer ends.

3. A counter-current interchanger comprising two plates of heat-conducting material spaced apart and coiled in volute form, a series of tubes of heat-conducting material extending longitudinally between and in contact with the plates and forming therewith a volute bank of alternating tubular conduits and intermediate passages, and a heat insulating packing separating the turns of the coiled plates and tubes from each other.

4. A counter-current interchanger comprising a volute bank of alternating tubular conduits and intermediate passages, formed by placing a series of tubes of heat-conducting material longitudinally between and in contact with two plates of heat-conducting material and coiling the plates and inclosed tubes in volute form, a packing of heat-insulating material between the turns of said coil, and manifolds connecting together the tubular conduits and intermediate passages, 90 respectively, both at the inner and outer ends of the coil.

5. A counter-current interchanger comprising two plates of heat-conducting material spaced apart and coiled in volute 95 form, a series of tubes of heat-conducting material extending longitudinally between and in conductive relationship with the plates and forming therewith a volute bank of alternating tubular conduits and intermediate 100 passages, manifolds respectively connecting together the ends of the tubular conduits and the intermediate passages both at the inner and outer ends of the coil, a heat-insulating packing separating the several turns of the coil from each other, and an outer casing insulated from and inclosing the coil.

CHARLES H. SMOOT.
